UNITED STATES PATENT OFFICE.

WILLIAM E. MARSHALL, OF MASPETH, NEW YORK.

CHECK-INDORSING MACHINE.

1,244,524.

Specification of Letters Patent. Patented Oct. 30, 1917.

Application filed May 3, 1916. Serial No. 95,087.

To all whom it may concern:

Be it known that I, WILLIAM E. MARSHALL, a citizen of the United States, residing at 7 Columbia Place, Maspeth, L. I., in the county of Queens and State of New York, have invented certain new and useful Improvements in Check-Indorsing Machines, of which the following is a specification.

10 This invention relates to an apparatus for indorsing or stamping checks or similar instruments written or printed upon sheets of papers, and its novelty consists in the construction and adaptation of the parts, as 15 will be more fully hereinafter pointed out.

In using an apparatus of this sort it is necessary to change the type whenever a change in indorsement or stamping is desired. Such changes must be made frequently and quickly, and this problem was not met by the apparatus of the Patent No. 1,128,801, nor elsewhere in the art. This apparatus is so constructed that without any tool the type can be changed quickly by 25 hand.

20 In the drawings there is shown a preferred form of apparatus embodying the invention, although it will be understood that it may be embodied in other forms 30 within the skill of persons versed in the art to which it relates, without departing from the principles upon which its operation is based.

35 In the drawings, Figure 1 is a vertical central section through the apparatus certain parts being shown in dotted outline; Fig. 2 is an enlarged sectional detail of the printing mechanism; Fig. 3 is a perspective of the separable sub-frame; Fig. 4 is a perspective of the ink roller and frame; Fig. 5 is a perspective of the detachable wheel; Fig. 6 is a perspective of the shaft on which the type carrier is mounted; Fig. 7 is a perspective of the type carrier.

extending arm having a terminal hook 50 and which detent is mounted to rotate on a cross rod 51 around which is coiled a spring 52 rigidly secured at one end to a swinging 5 type carrier frame 53 and provided with an upwardly extending loop 54 adapted to impinge against a cross rod 55. The frame 53 is provided with a slot 56. A coiled spring 57 is connected to the arm 45 and the detent 10 member 49.

The type-carrier comprises a central shaft 60 having near one end an indentation 61 and at the other rigidly secured to the shaft a disk 62 provided on one side with a spacing hub (not shown). A second disk 63 having a similar spacing hub 64 is adapted to be yieldingly and detachably secured to the shaft by a radial spring pin 65 the inner end of which is adapted to engage the indentation 61. A tubular shaft 66 mounted 15 on the shaft has rigidly secured to it at either end two wheels 67, 67 each having an interruption or truncated portion 68, 68 and alongside of one wheel 67 is a reduced portion 69 having a notch 70 adapted to be engaged by the hook 50. Between the two wheels 67, 67 is arranged a cylindrical sector 71 preferably of rubber and displaying suitable type indicated at 72 on its 20 curved surface 73.

The ends of the shaft 60 which project beyond the disks 62 and 63 engage the slots 56 in the frame 53 and by means of the coiled spring 52, the type carrier is continually pressed down against the revolving platen 25 which is provided with two annular grooves one of which is indicated at 250 (see Fig. 2) and in which grooves the lower ends of the fingers 44 are normally adapted 35 to rest.

The operation of the device is as follows: A number of the checks to be indorsed are assembled upon the shelf 12 convenient to the hand of the operator. The motor 15 is 40 then caused to operate by the means provided in any particular case and the platen 25 is thereby continually rotated, and through contact of the disks 62 with the surface of the platen the inner shaft 60 is 45 also continually rotated.

A check is then fed into the machine and coming between the disks 62 and the platen 25 is drawn downwardly until it contacts with the fingers 44 which rest lightly in the 50 annular grooves 250 of the platen, and lifting these fingers they tilt the arm 45 and its pin 46 engaging the slot of the detent member 48, this in turn moves the member 49 and consequently moves the hook 50 out of 55 the notch 70 and in contact with the outer surface of the hub 69 and permits the tubular shaft 66; (which has previously been detained from moving by the engagement of the hook and notch) to move. This rotates the wheels 67 and the type sector 71

and the type on the latter is brought into contact with the surface of the check and prints the proper legend thereon. The passage of the check between the platen and the printing sector permits the fingers to 70 drop back in their respective grooves, and the actions of the spring 57 keeping the hook pressed against the surface of the hub 69, the hook snaps into the notch 70 as soon as the revolution of the parts will permit 75 and the rotation of the type sector is stopped and the interruption 68 is again brought into position so the wheels 67 are no longer in contact with the platen.

The ink roller frame 32 presses down 80 upon the type carrier frame 53 and assists in the printing operation. As the sector in its revolution passes the ink roller it receives the proper amount of ink.

I claim:

1. In apparatus of the character set forth, the combination with a rotatable platen, of a swinging frame movable toward and from the same, a shaft journaled in the frame and removable therefrom, a type carrier frictionally mounted on the shaft to rotate therewith and removable therefrom when the shaft is detached from the frame, rollers carried by the shaft at the ends of the type carrier and engaging the platen to effect the 95 rotation of the shaft, one of said rollers being removable to permit the removal of the type carrier, and interlocking means between said rollers and shaft to hold the two 100 against accidental detachment and prevent their relative rotation.

2. In a device of the character described, a rotatable platen, an intermittently rotating type carrying device comprising a swinging frame, a type carrying device detachably 105 secured therein and means for yieldingly holding such device in its swinging frame, including an oscillating frame, an inking device carried thereby, a guard for this inking device and a spring adapted to hold the 110 guard in respect to this inking device and to hold the inking device frame against the type carrying device.

3. In apparatus of the character set forth, the combination with a platen, of a frame 115 movable toward and from the same, a type carrier in the frame coöperating with the platen, another frame movable toward and from the first frame and detachably engaged in the same, an inking roller journaled in 120 the second frame, a movable shield detachably bearing against the second frame, said shield covering the inking roller, and yielding means for urging the shield against the second frame and the second frame against 125 the first frame.

4. In apparatus of the character set forth, the combination with a support, of a rotatable platen journaled thereon, a swinging frame detachably mounted on the support 130

- and movable toward and from the platen, a rotatable type carrier removably mounted in the frame and coacting with the platen, a second swinging frame pivotally and 5 removably mounted on the support and detachably engaging the first frame, an inking roller journaled on the second frame, a shield pivotally mounted on the support and covering the inking roller, and means for 10 yieldingly urging the second frame in engagement with the first frame and thereby maintaining the inking roller in associated relation with the type carrier and the type carrier in associated relation with the platen.
- 15 5. In apparatus of the character set forth, the combination with a support, of a platen mounted thereon, a frame movably mounted on the support, a type carrier in the frame coöperating with the platen, a sec- 20 ond frame movable toward and from the first frame, an inking device in the second frame coöperating with the type carrier, a shield movably mounted over the second frame and inking device, and a spring bear- 25 ing against the support and shield for urging said shield against the second frame, the second frame against the first frame, and the type carrier of the first frame into coaction with the platen.
- 30 6. In apparatus of the character set forth, the combination with a support, of a platen
- mounted thereon, a frame pivotally mounted on the support, a rotatable type carrier in the frame coöperating with the platen, a second frame pivotally mounted on the sup- 35 port, an inking device in the second frame coöperating with the type carrier, a shield pivotally mounted over the inking device, and a spring engaged with the shield and with the support for yieldingly holding the 40 shield against the second frame and maintaining the inking device in coaction with the type carrier and the type carrier in coaction with the platen.
7. In apparatus of the character set forth, 45 the combination with a supporting frame, of a rotatable platen journaled thereon, a swinging frame pivoted on the support, a type carrier rotatably mounted in the frame and coöperating with the platen, an inking 50 roller frame, a shield member having a common pivotal mounting on the supporting frame, an inking roller journaled in the last mentioned frame beneath the shield and coöperating with the type carrier, and a 55 coiled spring on the mounting for the inking roller frame and shield, said spring being connected to the supporting frame and the shield.

In testimony whereof I affix my signa- 30 ture.

WILLIAM E. MARSHALL.
